UNITED STATES PATENT OFFICE.

WALTER HUBER, OF PFORZHEIM, GERMANY.

DESIGN FOR A COMBINED TIMEPIECE AND SUPPORT.

Application filed October 20, 1926. Serial No. 19,431. Term of patent 7 years.

To all whom it may concern:

Be it known that I, WALTER HUBER, a citizen of the German Empire, residing at No. 55 Luisenstrasse, in the city of Pforzheim, Germany, have invented a new, original, and ornamental Design for a Combined Timepiece and Support, of which the following is a specification, reference being had to the accompanying drawing, forming part thereof.

Fig. 1 is a side elevation of the new design for the combined timepiece and support, with the cover for protecting the crystal in open position; Fig. 2 shows a front view.

I claim:—

The ornamental design for a combined timepiece and support, as shown.

WALTER HUBER.
